ATTORNEYS

UNITED STATES PATENT OFFICE.

HUGH F. WAGLEY, OF MINERAL WELLS, TEXAS.

DOUCHE TABLE.

Application filed August 11, 1925. Serial No. 49,625.

To all whom it may concern:

Be it known that I, HUGH F. WAGLEY, a citizen of the United States, and resident of Mineral Wells, in the county of Palo Pinto 5 and State of Texas, have invented certain new and useful Improvements in Douche Tables, of which the following is a specification.

This invention relates to improvements in 10 medical appliances, more particularly tables and the like, and it consists of the constructions, combinations and arrangements herein described and claimed.

An object of the invention is to provide 15 a douche table designed particularly for the treatment of the diseases of women, the construction being extremely simple yet sturdy, and of such design that water will drain rapidly with little likelihood of passing 20 over the sides.

Other objects and advantages appear in 25 the following specification, reference being had to the accompanying drawing, in which—

Figure 1 is a perspective view of the improved douche table.

Figure 2 is a detail sectional view taken on the line 2—2 of Figure 1.

In carrying out the invention provision is 30 made of a support 1 which comprises upper and lower pairs of legs 2 and 3. These legs are braced near the bottom by a bottom frame 4 which extends from leg to leg as shown. The lower legs 3 are shorter than the upper legs 2 thereby giving the table top 35 a slant in the downward direction.

The upper ends of the legs are appropriately affixed to a top frame 6 (Fig. 2), which, like the frame 4, extends around from leg to 40 leg and furnishes a perfectly stable support for the table top. The table top is made of metal. The ends and sides are turned down and under the top angle iron 6 as at 7. This arrangement not only provides a smooth surface at the corners of the top angle iron but 45 also prevents the lodgment of impurities such as might be expected to collect around a device of this character.

A drain pan 8 is incorporated in the table

top 5. The pan may be made integrally 50 with the table top or it may be affixed in any approved and known manner. The table top has a concave depression 9 which slopes toward the foot of the table and to one edge of an opening in the table top. The concavity permits fluid to flow into the drain pan which drain pan is fitted around said opening. A spout 10 serves the purpose of a discharge for the drain pan.

The spout shown is of simple nature, and 60 in practice is usually made to discharge into a bucket or other receptacle that is set under the table. It would be an obvious expedient to attach a hose to the spout, or to incorporate a valve, although as already stated 65 the usual mode of use is to simply set a bucket under the spout.

Diagonal braces 11, situated between the various legs and the top frame 6 contribute 70 considerable strength to the general construction. The table top is equipped with a headrest 12 and a foot rest 13. In practice, the head rest 12 may be supplemented by a pillow, but this has not relationship 75 to the invention.

The use of the table is obvious. Upon 80 the administration of a douche any water flowing upon the upper part of the table top will be directed into the drain pan 8 by the concavity 9. The tendency of the water 85 to drain is furthered by the inherent slant of the table from head to foot. The extreme simplicity of the table promotes the easy and cheap manufacture thereof, making it possible to extend the use of the table 90 to private homes. The table is intended largely for use in sanitariums, hospitals and the like, and being of simple construction is readily cleaned to comply with the demands for sanitation.

While the construction and arrangement 95 of the improved table is that of a generally preferred form, obviously modifications and changes may be made without departing from the spirit of the invention or the scope of the appended claim.

I claim:

A sanitary douche table comprising a top

- frame, pairs of legs at the end extremities of the table of which one pair is shorter than the other, a bottom frame extending from leg to leg near the bottom of the legs, 5 a single piece, substantially smooth table top applied to and fitted around the top frame, the head and foot portions of said top lying in the same plane, said top being provided

with an opening therein near the foot thereof and a concaved depression sloping toward the foot of said table to one edge of said opening, and a drain pan having an outlet therein made integral with said top and fitted around said opening. 10

HUGH F. WAGLEY.
